(57) **CLAIM**

We claim the ornamental design for a quad blade unit, as
shown and described.

DESCRIPTION

FIG. 1 is a first top perspective view of a quad blade unit of
the present disclosure;
FIG. 2 is a first bottom perspective view of the quad blade
unit of FIG. 1;
FIG. 3 is a second top perspective view of the quad blade
unit of FIG. 1;
FIG. 4 is a second bottom perspective view of the quad blade
unit of FIG. 1;
FIG. 5 is a first side elevational view of the quad blade unit
of FIG. 1;
FIG. 6 is a second side elevational view of the quad blade
unit of FIG. 1;
FIG. 7 is a front elevational view of the quad blade unit of
FIG. 1;
FIG. 8 is a rear side elevational view of the quad blade unit
of FIG. 1;
FIG. 9 is a top plan view of the quad blade unit of FIG. 1;
and,
FIG. 10 is a bottom plan view of the quad blade unit of FIG.
1.
The broken lines depict portions of the article that form no
part of the claimed design.
